UNITED STATES PATENT OFFICE.

LOUIS L. WHITE, OF DORRIS, CALIFORNIA, ASSIGNOR TO PLATINUM ELECTRIC
INCUBATOR CO., OF DORRIS, CALIFORNIA, A CORPORATION OF CALIFORNIA.

THERMO CIRCUIT-CLOSER.

1,151,142.

Specification of Letters Patent. Patented Aug. 24, 1915.

Original application filed April 19, 1910, Serial No. 556,338. Divided and this application filed February 18, 1913. Serial No. 749,267.

To all whom it may concern:

Be it known that I, LOUIS L. WHITE, a citizen of the United States, residing at Dorris, in the county of Siskiyou and State of California, have invented certain new and useful Improvements in Thermo Circuit-Closures, of which the following is a specification, reference being had therein to the accompanying drawing.

10 This invention relates to thermo circuit closures and has for its object the production of a simple and efficient mechanism which will automatically close a circuit in order to automatically actuate a draft as soon as the temperature within a desired compartment has reached a predetermined point.

20 Another object of this invention is the production of a simple and efficient means for regulating the circuit closure so as to allow the same to be adjusted whereby the circuit closing device may be caused to actuate at a predetermined time.

25 With these and other objects in view, this invention consists of certain novel constructions, combinations and arrangements of parts, as will be hereinafter fully described and claimed.

30 In the accompanying drawing: Figure 1 is a fragmentary sectional view through a portion of an incubator showing the automatic draft arrangement and means for actuating or regulating the circuit closure. Fig. 2 is a top plan view of the circuit closer. Fig. 3 is a front view of the circuit closing apparatus. Fig. 4 is a detail perspective of one end of the regulating rod adapted to coöperate with the circuit closing apparatus illustrated in Fig. 3.

40 In carrying out this invention an incubator of the usual type is employed provided with a heating chamber 1 and a small chamber 2 at the end of the incubator adjacent the heating chamber 1. The 45 electrical mechanism, which for practical purposes is of a small size, is located in the chamber 2. The incubator is provided with a hinged cover or damper 4 located in its top to close the opening 3 which is operated 50 by an electrical apparatus of the desired structure, which electrical apparatus is controlled by means of a circuit closer of the thermo type, which is described as follows:

55 A suitable thermostat is suspended in the heating chamber 1 above the eggs or other

objects placed upon the floor thereof, and is preferably constructed of a supporting block 19 which is suspended from the upper side of the heating chamber 1 as shown in Fig. 1, and preferably consists of a metal coil 20 composed of strips of brass and steel soldered together, one end of said coil 20 being secured in the end of the shaft 21, which shaft projects between the plate 22 secured to the block 19. On the other end of the coil 20 is mounted the thermostatic lever arm 23, which arm is provided with a twisted end 24 which twisted end projects between the needle contact points 25 and 26 and has its flat side faces located intermediate the contact points 25 and 26. In order to adjust the thermostatic lever 23 in the proper position between said contact points in case the spring 20 should become twisted or forced out of its normal position, the arm 28 is mounted on the shaft 21 and is connected by a connecting rod 29 with a lever arm 30, which arm is mounted on a shaft 31, said shaft 31 projecting across the heating chamber 1 as illustrated in Fig. 1 and terminating at its outer end in a plate 31' mounted on the outside of the incubator as shown in Fig. 4. The plate 31' is provided with an arc-slot 32 in which travels the arm 33 which arm 33 is connected to the shaft 31. 35 From the foregoing description, it will be seen that by swinging the arm 33 in the slot 32, the thermostatic arm 23 may be adjusted laterally to the proper position between the contact points 25 and 26 so as to regulate the time or the amount of swing necessary for the arm in order to close a contact between one of the points 25 and 26. Of course, the points 25 and 26 are each mounted on a suitable insulating block 37 and are connected to the binding posts 26' and 27'. It should be understood that the contacts 24, 25 and 26 control circuits which operate a motor, which motor is adapted to control the door 4 through the 40 medium of the rod 43 illustrated in Fig. 1 of the drawings.

45 The construction and operation of the electrical mechanism is not disclosed further in this application since this application is a division from the application previously filed by me and upon which U. S. Letters Patent No. 989,462 was issued on April 11, 1911.

50 From the foregoing description, it will be

seen that a very simple and efficient device has been produced whereby the thermostat may be regulated to actuate at a predetermined point and without opening the incubator or without having access to the interior thereof.

Having thus described the invention, what is claimed as new, is:—

In a device of the character described, the combination with a casing, of a thermostat mounted therein and including circuit terminals and a thermostatic arm coöperating with said terminal, a shaft upon which the arm is mounted, a crank arm carried by the shaft, an adjusting shaft extending through and projecting externally of the casing, a crank arm carried by the adjusting shaft

within the casing, a link connecting the two crank arms, a plate mounted on the outside of the casing and through which the adjusting shaft extends, said plate being provided with an arc-shaped guide slot, and a handle carried by the external end of the adjusting shaft and engaging the guide slot of the plate for limiting the swinging movement of said shaft and constituting means for holding said shaft against longitudinal movement upon said casing.

In testimony whereof I hereunto affix my signature in presence of two witnesses.

LOUIS L. WHITE.
